UNITED STATES PATENT OFFICE

149,028

DESIGN FOR A BELT BUCKLE

Herbert J. Shepherd, St. Louis, Mo.

Application March 24, 1947, Serial No. 137,837

Term of patent 14 years

(Cl. D17—1)

To all whom it may concern:

Be it known that I, Herbert J. Shepherd, a citizen of the United States, residing at St. Louis, in State of Missouri, have invented a new, original, and ornamental Design for a Belt Buckle, of which the following is a specification, reference being had to the accompanying drawing, forming part thereof.

In the drawing:

Figure 1 is a frontal elevational view of a belt buckle showing my new design with the two parts thereof linked together.

Figure 2 is an edge view, looking towards the bottom of Figure 1.

Figure 3 is a rear elevational view, the parts of the buckle being shown as linked together.

Figure 4 is a frontal elevational view, showing the parts of the buckle as disconnected.

Figure 5 is an inner edge view of the left hand link of the buckle, looking towards the inner edge of the left hand link as shown in Figure 4.

Figure 6 is an inner edge view of the right hand

link, looking towards the inner edge of the right hand link as shown in Figure 4.

Figure 7 is a perspective view, looking in end-wise towards the rear side of the connected links, with the right hand link of Figure 4 positioned forwardly.

I claim:

The ornamental design for a belt buckle as shown and described.

HERBERT J. SHEPHERD.
